UNITED STATES PATENT OFFICE

ALBERT C. TITCOMB, OF NEWTON, MASSACHUSETTS

APPARATUS FOR FORMING CONCRETE PILES IN THE GROUND

Application filed April 27, 1928. Serial No. 273,219.

This invention relates to improvements in method and apparatus for forming concrete piles in the ground, and the object thereof is to provide a novel method and apparatus which will more efficiently produce the hole to receive the concrete which forms the pile and which will enable concrete piles to be properly constructed at a minimum cost of material and labor.

10 In usual processes of forming concrete piles in the ground, the hole to receive the concrete is formed by driving into the ground a tubular forming member having a conical, cast iron point having substantially the same maximum diameter as the diameter of the driving form and provided with a shank which extends into, and substantially fits, the lower end of the driving form. When the driving form has been

15 sunk until the point encounters a rigid material, or when the resistance to further driving exceeds a predetermined minimum force, the driving form is filled with concrete and the form pulled out, additional concrete being poured in, if necessary, during the extraction of the form.

In some cases previously cast conical concrete points have been employed, and in others conical concrete points armored with a metallic shell, or expensive cast steel points have been used.

When in the use of such apparatus the driving form is forced through a stratum containing stones of considerable size the conical metallic or other points are frequently broken and great difficulty thereafter encountered in properly sinking the form to a sufficient depth to give the pile a suitable foundation.

40 Furthermore, where a driving point of the character specified, having the same diameter as that of the driving form, is driven through a stratum of this character the form will become wedged between large pieces of rock so that it can be withdrawn

only with great difficulty and in many instances requiring the use of a water jet to shift the location of the rock.

Again, concrete piles are frequently required to be driven among old wood piles and where a conical point, such as above described, of approximately the same size of the driving form, is employed and driven among such old piles, the removal of the form, after it has been filled with concrete, has proved very difficult and some times impossible.

The present invention is designed to overcome these and other difficulties which are encountered in the production of concrete piles in the ground.

The method of forming concrete piles in the ground, in accordance with my invention, comprises driving into the ground a preparatory pile having at its lower end a detachable, substantially flat, infrangible metallic driving head of greater area than the area of the lower end of said form, then filling the chamber of the form, to a greater or less degree, with concrete and withdrawing the form, thereby leaving the flat metallic head as a permanent footing for the pile.

It has been found in actual practice that a driving form having a flat infrangible metallic head, preferably of rolled or forged steel, such as boiler plate, and which may in fact be made of less thickness than the wall of the driving form, no breakage of the point or head will occur by reason of engagement with stones or rocks.

Furthermore, by the use of such flat penetrating heads a suitable foundation for the pile may be made upon strata of sand, or other material, which would not properly support a pile having as a footing the conical penetrating point.

By employing a flat penetrating point of this character, which is of larger diameter than the diameter of the driving form, the

driving form can be readily withdrawn after having been filled with concrete, thereby affecting a great saving in time and labor over usual methods.

5 Usual types of cast iron conical points for driving forms heretofore employed are of very considerable weight approximating one hundred pounds each. In the present invention the penetrating head, which is in the 10 form of a substantially flat infrangible steel plate preferably having a peripheral flange surrounding the lower end of the driving form, is much lighter, such flat penetrating heads weighing approximately forty pounds 15 having been successfully employed without breakage under conditions which caused frequent breakage of the heavier cast iron conical heads.

The production of such flat penetrating 20 heads is relatively inexpensive and a considerable saving in cost of transportation is effected where large numbers of concrete piles are being formed.

Such flat heads are of greater effective 25 area than the conical heads and give a greater bearing surface which in some soils permits the use of a much shorter pile, thus decreasing the cost of the pile. Furthermore, the flat surface of the head in many soils 30 gives a better bearing, for example, where piles are driven to hard material which cannot be penetrated by the conical point more than an inch or two, the bearing surface on the hard material is very limited, where- 35 as with the flat surface of the penetrating head embodying the present invention the whole area of the head is in contact with the hard material thus giving a greater factor of safety.

40 A preferred form of apparatus embodying the present invention is illustrated in the accompanying drawing, in which,

Fig. 1 is a vertical sectional view of a driving form having a flat metallic, preferably steel, penetrating head thereupon and sunk into the ground;

Fig. 2 is a detail view of the same showing a packing between the junction of the lower end of the driving form and a flat 50 penetrating head, the packing being enclosed within the flange of the head which surrounds the lower end of the driving form;

Fig. 3 is a sectional view on line 3—3 Fig. 52, viewed downwardly, a portion of the wall of the form being broken away to illustrate the preferred form of packing which is in the form of a coiled rope packed with grease;

Fig. 4 is a detail vertical sectional view of a concrete pile formed in accordance with the present invention, the flat penetrating head forming a footing for the pile;

Fig. 5 is a detail vertical sectional view 65 of a slightly modified form of substantially

flat penetrating head in which the central portion of the head is spherically convexed downwardly; and,

Fig. 6 is a detail vertical sectional view, 70 similar to Fig. 5, of another form of substantially flat penetrating head, the central portion of which is of conical form.

The driving form, as illustrated in Fig. 1, 75 comprises a tube 1, preferably but not necessarily of cylindrical form, having a flat lower end. A flat, or substantially flat, penetrating head 2, preferably of rolled or forged steel, engages the lower end of the driving form and is of somewhat greater diameter or area than that of the lower end of the driving form. The penetrating head 2 is provided with means presenting a shoulder to prevent undue lateral displacement relatively to the lower end of the driving head. In the particular form illustrated the driving head has an upwardly extending peripheral flange 3 which surrounds the lower end of the driving tube.

80 In the use of the apparatus described the penetrating head 2 may be placed upon the soil at the spot where the pile is to be driven, the driving form 1 superimposed thereupon within the peripheral flange 3, and a suitable block or head placed upon the upper end of the driving form, and the form forced downwardly by blows, hydraulic pressure, or otherwise, as is usual.

85 It is found in actual practice that where stones or rocks are encountered by the driving head, the engagement with such rocks is such that they will be generally forced laterally out of the path of the driving form.

90 Inasmuch as the head 2 is of greater area than the area of the lower end of the driving form, the rocks will thus be forced laterally a sufficient distance to prevent wedging against the wall of the driving form so that the driving form may be readily withdrawn after the form has been driven to such depth 95 that the head engages an impenetrable medium, or engages a stratum affording the required degree of resistance to further driving.

100 When the form has thus been driven down it is filled with concrete and withdrawn in the usual manner, the concrete, after withdrawal of the form, filling the hole produced by the apparatus above described. The head, which is, of course, detachable from the driving form, remains at the lower end of the hole and forms a flat footing for the concrete with the peripheral flange enclosing the lower end of the concrete pile.

105 This flat footing provides a more even distribution of the strains imposed upon the pile when a structure is superimposed upon it and consequently provides a much firmer foundation than that which would be provided by a conical point, the effective area 110

115 of the supporting portion of which is fre- 115

quently much less than the cross sectional area of the lower end of the conical pile.

Where concrete piles are to be formed in a water-containing soil, it is desirable that 5 means shall be provided to prevent accumulation of water within the driving form during the driving thereof as such water would otherwise have to be removed before the concrete is poured into the pile in order to insure 10 a proper consistency of concrete at the lower end of, or throughout, the pile.

The present invention permits a proper water-tight seal between the lower end of the driving form and the head to be employed 15 as the sealing mechanism will be properly retained within the peripheral flange which surrounds the lower end of the driving form.

A packing of fibrous material containing 20 a water-repellant substance is employed. A preferred packing, which is illustrated in Figs. 2 and 3, comprises a coil of rope 4 thoroughly impregnated with heavy grease, the rope being coiled in a flat spiral within 25 the flange 3 and preferably extending beneath the lower end of the driving member as illustrated in Fig. 2.

Other forms of substantially flat penetrating heads are illustrated in Figs. 5 and 6. 30 In the construction illustrated in Fig. 5 the substantially flat plate, which forms the penetrating head, has an annular flat portion 5, while the central portion 6 is convexedly curved downwardly. The plate is provided 35 with a peripheral flange 3 to enclose the lower end of the driving member as above described.

In the construction illustrated in Fig. 6 the substantially flat penetrating head presents 40 an annular flat portion 7 and a central, slightly conical, portion 8. In this form, as in the other, the penetrating head is provided with the peripheral flange 3 which encloses the lower end of the driving form. In 45 both of these constructions the lower end of the driving form rests upon the flat annular portion of the head.

It has been found in practice that where substantially flat infrangible steel plates are 50 employed for penetrating heads, plates of considerably less thickness than the thickness of the wall of the driving form may be successfully used.

As a matter of fact, steel plates having 55 a thickness of three-eighths inch and provided with peripheral flanges have been successfully employed as penetrating heads for driving forms the walls of which are three-fourths inch in thickness, and driving forms 60 having such heads have been successfully driven in soil conditions in which it was quite impossible to drive similar forms having cast iron conical points.

One of the advantages of the present invention is particularly illustrated in Fig. 4

which illustrates a concrete pile produced after a driving form had been sunk through the soil condition, comprising a fill A of several feet, with a sand stratum B therebeneath varying in thickness, with a clay stratum C therebeneath. In driving the form for this pile rocks D were encountered which were forced laterally from the path of the driving form by the larger head of the pile. When the flat driving head had reached the stratum B of sand it presented a sufficient area properly to support the pile, where with usual conical points the supporting area in certain portions of the sand stratum was of insufficient thickness to provide suitable resistance requiring the use of a pile several feet longer than that which was required for piles having the flat footings provided by the flat penetrating head embodying the present invention.

It has been found that the cost of constructing concrete piles with forms having flat steel penetrating heads is considerably less than the cost of constructing similar concrete piles with forms having conical cast iron points for the reason that with the latter a considerable amount of breakage occurs in soils where obstructions are found. When the point breaks it results not only in the loss of the point itself, but in most cases in damage to the driving form. These forms are very expensive and the loss of a few inches or a few feet is a serious consideration. Furthermore, the delay occasioned by damage to the driving form increases the ultimate cost of the pile. Where the present invention is employed no such breakage of the penetrating head has been found to occur under any conditions of service.

It will be understood that the embodiment of the invention disclosed herein is of an illustrative character and is not restrictive, and that the term "substantially flat" is intended to embrace not only constructions such as are illustrated in the drawing, but other equivalent constructions adapted for the same purpose and operating in a like manner.

Having thus described the invention, what is claimed as new, and desired to be secured by Letters Patent, is:

1. An apparatus for forming concrete piles in the ground comprising a cylindrical driving form, a substantially flat steel penetrating head, of greater area than that of the lower end of said driving form, engaging the lower end of said driving form and having a peripheral flange enclosing said lower end and spaced apart therefrom, and a yieldable packing of fibrous material containing a water-repellant substance within said flange.

2. An apparatus for forming concrete piles in the ground comprising a cylindrical driving form, a substantially flat steel pen-

trating head, of greater area than that of the lower end of said driving form, engaging the lower end of said driving form and having a peripheral flange enclosing said lower end and spaced apart therefrom, and a packing comprising a coil of rope and grease within said flange having a portion thereof intermediate of the lower end of said driving form and head.

10 In testimony whereof, I have signed my name to this specification.
